UNITED STATES PATENT OFFICE

92,965

DESIGN FOR AN AUTOMOBILE LIGHT

Albert W. Kandetzki, Stamford, Conn.

Application May 14, 1934, Serial No. 51,774

Term of patent 7 years

To all whom it may concern:

Be it known that I, ALBERT W. KANDETZKI, a citizen of the United States, residing at Stamford, county of Fairfield, State of Connecticut, have invented a new, original, and ornamental Design for an Automobile Light, of which the following is a specification, reference being had to the accompanying drawing, forming part thereof.

Fig. 1 is a front elevation of an automobile light showing my new design;

Fig. 2 is an end elevation thereof; and

Fig. 3 is a bottom plan view.

I claim:

The ornamental design for an automobile light, substantially as shown.

ALBERT W. KANDETZKI.
